US00D941887S

(12) **United States Design Patent** (10) **Patent No.:** **US D941,887 S**
(45) **Date of Patent:** **** Jan. 25, 2022**

(54) **BIT FOR A GROUND ENGAGING MACHINE IMPLEMENT**

(71) Applicant: **Caterpillar Inc.**, Peoria, IL (US)

(72) Inventors: **David Parzynski**, Peoria, IL (US);
Thomas Marshall Congdon, Dunlap, IL (US)

(73) Assignee: **Caterpillar Inc.**, Peoria, IL (US)

(**) Term: **15 Years**

(21) Appl. No.: **29/779,367**

(22) Filed: **Apr. 19, 2021**

Related U.S. Application Data

(63) Continuation of application No. 29/753,744, filed on Oct. 1, 2020, now Pat. No. Des. 924,944, which is a continuation of application No. 29/738,586, filed on Jun. 18, 2020, now Pat. No. Des. 907,072, which is a continuation of application No. 29/644,016, filed on Apr. 13, 2018, now Pat. No. Des. 890,816.

(57) **CLAIM**

The ornamental design for a bit for a ground engaging machine implement, as shown and described.

DESCRIPTION

FIG. 1 is a front, left perspective view of a bit for a ground engaging machine implement showing our new design; FIG. 2 is a rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

1 Claim, 4 Drawing Sheets
